RAPPING DEVICE

Anthony S. Gannone, Bound Brook, N. J., assignor to Research Corporation, New York, N. Y., a corporation of New York

Application January 4, 1943, Serial No. 471,289

7 Claims. (Cl. 259—1)

This invention relates in general to means for jarring or vibrating apparatus utilized in removing suspended particles from gases. It relates in particular to apparatus for dropping a missile such as a metal ball upon the electrode structures of electrical precipitators, precipitators of the Cottrell type, for instance, to remove deposited material from the electrodes of the precipitators.

The invention has for its principal object the provision of apparatus for raising a striking member to a level above an anvil associated with an electrode structure and allowing the striking member to fall freely under the influence of gravity upon the anvil.

A more particular object of the invention is to provide a unitary ball handling device arranged for rotary or oscillating movement about a horizontal axis which will repeatedly pick up a ball, carry it to a position approximately over an anvil associated with an electrode structure, and then release it to fall by gravity upon the anvil.

In the following description of the invention it is to be understood that the term "electrode structure" may refer to a single electrode, such as a collecting electrode of the plate type, or to means which support or steady one or more electrodes, such as the bus bars of discharge electrode systems. The invention can be applied, of course, to the walls or other parts of an electrical precipitator upon which particulate material is electrically or mechanically deposited and the removal of the material therefrom is necessary if the precipitator is to operate continuously at unimpaired efficiency.

A preferred embodiment of the invention provides a unitary means for rapping with a fracture resisting metal ball, comprising a horizontal shaft capable of rotary motion, a ball lifting member attached to the shaft and having at least one arm projecting outwardly from the shaft, and a hammer ball, the latter being retained within the lifting member in such a manner that it can move therein and can project partially through the confining elements of the arm or arms to contact the surface of the anvil or anvils it is adapted to strike. The ball lifting member is further characterized in that it is so shaped and constructed that, upon rotation of the shaft, the arm portion or portions are capable of lifting the ball above an anvil to be struck, provision being made for retaining the ball in the elevated position until an arm portion moves into a position which provides a path to the anvil for the

ball, whereupon the ball drops down the arm and projects through the confining elements of the arm far enough to strike the anvil. The arm then lifts the ball as before and the cycle is repeated.

5 The manner in which the objects mentioned above and other objects are realized by the invention will be set forth in the following description, illustrated by the accompanying drawings wherein:

10 Fig. 1 illustrates in side elevation apparatus comprising one embodiment of the invention;

Fig. 1a is a fragmentary detail of the apparatus of Fig. 1;

15 Fig. 1b is a fragmentary detail in partial section of a modification of the apparatus of Fig. 1;

Fig. 1c is a fragmentary detail in partial section of another modification of the apparatus of Fig. 1;

20 Fig. 2 is a bottom view of the apparatus shown in Fig. 1;

Fig. 3 is a diagrammatic representation of one method of operating the apparatus shown in Figs. 1 and 2;

25 Fig. 4 is a diagrammatic representation of another method of operating the apparatus shown in Figs. 1 and 2;

Fig. 5 is a diagrammatic representation of a different method of operating apparatus similar to that of Fig. 1;

30 Fig. 6 is a diagrammatic representation of a modified form of the invention;

Fig. 7 is a side elevation of another modification of the invention;

Fig. 8 is a side elevation in partial section of a further modification of the invention, and

35 Fig. 9 is a perspective view of a still further modification of the invention.

The apparatus illustrated in Figs. 1 and 2 comprises a track or guide structure including ball lifting arm 14 and ball retaining recess 15, a striking ball 16 within the track structure, and a rotatable shaft 17 to which the track structure is attached. Two members 11, which may be iron castings, fastened together with transverse bolts

40 12 and cap screws 13, make up the track structure and each member 11 has under its knee a pad 16 containing a semi-circular depression in which shaft 17 is retained. A saddle plate 18, with a semi-circular depression that is complementary to

45 50 the depressions in members 11 and has a partially serrated surface, clamps over shaft 17 and engages toothed key 20 which is embedded in shaft 17, as shown more fully in Fig. 1a. Shaft 17 is 55 mounted in bearings (not shown) and the shaft

is rotated or oscillated by any suitable agency, none being shown in the drawings.

The cross-section of the retaining recess 15 need be but slightly greater than the maximum section of the ball but the cross-section of the lifting arm 14, preferably, increases in the plane of rotation as the free end of the arm is approached. This is because the velocity of the ball as it starts to drop from position 10' has a horizontal component and takes a parabolic path in its descent. Slot 22, through which ball 10 projects to strike anvil 30, has an elongated shape to allow for the out-of-vertical path of the dropping ball and to make it unnecessary to determine exactly where the ball will strike the anvil. The anvil 30 is mounted on member 31 which carries electrode supports 32 from which electrodes 33 are suspended. Member 31 is supported by insulating bushings 34.

The lower end of arm 14 in Figs. 1 and 2 is shaped to ride over the anvil 30. In Fig. 1c a modified form of the end of arm 14 is shown in which the sides 19 depend below the top surface of an anvil 30'.

In the modification shown in Fig. 1b, means is provided for positively ejecting the ball from the recess 15a, comprising a finger 35 angularly fixed to arm 36 carrying weight 37 and pivotally mounted at the end of recess 15a so that when arm 14 is in position to guide the ball to the upper surface of the anvil, finger 35 swings into position to eject the ball from recess 15a. Lateral shelf members 38 in recess 15a support the ball in said recess when in the position indicated in dotted lines.

Fig. 3 indicates how, upon oscillating shaft 17 and raising the end of lifting arm 14, containing the ball, to approximately horizontal position indicated in dotted lines, the ball is made to roll into recess 15 where it remains until the arm returns to a position over the anvil when it rolls out of the recess and falls to the anvil. The slope of the bottom of recess 15 with relation to the free falling path provided by arm 14 must be such that the ball will roll out of the recess when and only when arm 14 is properly positioned over the anvil or is approaching the proper position, allowance being made for the time necessary for the movement of the ball. These relative positions can be determined by trial, test apparatus which permits the angle between portion 14 and portion 15 to be altered being used to advantage in determining the desired relationships. When the apparatus is oscillated as shown in Fig. 3, interior surface s of arm 14 serves as a runway for the return of the ball to recess 15.

Fig. 4 indicates how the apparatus operates when shaft 17 is continuously rotated. The ball now drops once every revolution of the shaft or after a shaft movement of 360 degrees. With an oscillating shaft, as indicated in Fig. 3, on the other hand, the ball drops every time the shaft turns, say, 96 degrees, and returns to its original position, or a total of 192 degrees. Surface s' of arm 14 serves as a runway for the return of the ball to recess 15 when the apparatus is rotated as indicated in Fig. 4.

In the modification shown in Fig. 5, the track structure is pivoted about shaft 17 at a point near the anvil. Arm 14b and recess 15b function on oscillation of the track structure about the shaft similarly to the corresponding arms and recesses of Figs. 1-4.

In the form of the invention shown in Fig. 6, the symmetrical arms 40 function alternately as

recesses and as guideways for the missile 10 as the track structure oscillates between the position shown in solid lines and the position indicated in broken lines at A.

Figs. 7 and 8 show track structures comprising symmetrical paired arms which alternately cause the missile contained therein to strike paired anvil members 30.

In the apparatus of Fig. 7 the track structure comprises symmetrically paired arms 41 each having a ball retaining recess 42 and mounted for oscillation about shaft 17 so that in alternation the ball is guided to fall upon one and the other of the paired anvils at the end positions of oscillation defined by stops 43. In operation, as the track structure oscillates about shaft 17 from the position shown in full lines the ball is carried upward in the end of lower arm 41 until the arms pass just beyond the horizontal position when the ball will run down the arm and drop into the first recess 42. As the track structure continues its oscillation toward the position shown in dotted lines, the ball remains in the first recess which in the dotted line position becomes the uppermost recess and in this position the ball drops out of the recess and falls substantially freely onto right-hand anvil 30.

In the apparatus of Fig. 8 the paired arm members 44 act alternately as ball retaining recess and ball guides to cause the ball to strike the paired anvils in alternation as the track structure oscillates about shaft 17.

The enclosures illustrated in Figs. 1 and 2, and 5-8, are shown imperforate except for the slots through which the balls project in striking the anvils, but the walls of the enclosures can be perforate for purposes of reduction in weight, observation and removal of dust. The apparatus illustrated in Fig. 9 realizes these purposes. The track structure comprises top plate 50, bottom plate 58, and guide members 55, 56 and 57 which are attached to both plates and tie the whole into a unit structure. Plate 50 has an opening 51, covered with a removable plate 52, through which a ball may be introduced. Plate 50 includes lugs 53 bent down at right angles to the face of the plate to support retaining plates 54 for shaft 17, which serves to oscillate or rotate the structure. Retaining bars 57 are bent to provide a recess 61 for retention of the striking ball (not shown) for the purpose described in connection with other forms of the invention. Guide members 55, 56 and 57 obviously can be abbreviated except to the extent they are needed to hold the apparatus together, to provide a runway for the ball, and to prevent the ball from leaving the runway, say, when bouncing after striking the anvil. A slot 59 in plate 58 permits the striking ball to project through to an anvil (not shown).

In applying the invention to electrical precipitators of the Cottrell type, one or a plurality of the striking units described above can be used to rap or vibrate a single precipitator, depending upon the size of the precipitator and the need for rapping it. The design of the precipitator will determine the position of the anvils and the manner of their attachment to the electrode structures or other precipitator elements which are to be rapped or vibrated.

I claim:

1. Apparatus for rapping material-collecting structures, comprising an anvil mounted on the material-collecting structure, a trackway for a missile comprising a missile-guiding portion and

a missile-retaining portion, said trackway being pivotally mounted for movement with respect to the anvil from a position in which a missile will be guided by the guiding portion into the retaining portion to a position in which a missile will be released from the retaining portion and guided by the guiding portion into substantially free impact upon said anvil.

2. Apparatus for rapping material-collecting structures, comprising an anvil mounted on the material-collecting structure, a trackway for a missile comprising a missile-guiding portion and a missile-retaining portion, said trackway being pivotally mounted for movement with respect to the anvil in a vertical plane from a position in which a missile will be guided by the guiding portion into the retaining portion to a position in which a missile will be released from the retaining portion and guided by the guiding portion into substantially free impact upon said anvil.

3. Apparatus for rapping material-collecting structures, comprising an anvil mounted on the material-collecting structure, a pivotally mounted trackway for a missile rotatable with respect to the anvil into position to guide the missile into impact upon said anvil, and means for retaining said missile at a point in said trackway spaced from the anvil when the trackway is in positions other than the position at which the missile will be guided into impact upon the anvil.

4. Apparatus for rapping material-collecting structures, comprising an anvil mounted on the material-collecting structure, a pivotally mounted trackway for a missile rotatable with respect to the anvil into position to guide the missile into impact upon said anvil, and having a recess constructed and arranged to retain said missile at a point in said trackway spaced from the anvil when the trackway is in positions other than

the position at which the missile will be guided into impact upon the anvil.

5. Apparatus for rapping material-collecting structures, comprising an anvil mounted on the material-collecting structure, a pivotally mounted trackway for a missile rotatable with respect to the anvil into position to guide the missile into impact upon said anvil and having a recess constructed and arranged to retain said missile at a point in said trackway spaced from the anvil when the trackway is in positions other than the position at which the missile will be guided into impact upon the anvil, and means for ejecting said missile from said recess when the trackway is in the position at which the missile will be guided into impact upon the anvil.

6. Apparatus for rapping material-collecting structures, comprising an anvil mounted on the material-collecting structure, a trackway for a missile pivotally mounted for oscillation with respect to the anvil between terminal positions in which the trackway guides the missile into impact on said anvil, and means for retaining the missile at a point in said trackway spaced from said anvil at positions of said trackway other than said terminal position.

7. Apparatus for rapping material-collecting structures, comprising a pair of spaced anvils mounted on the material-collecting structure, a trackway for a missile pivotally mounted for oscillation with respect to the anvils between terminal positions in which the trackway guides the missile into impact upon said anvils in alternation, and means for retaining the missile at a point in said trackway spaced from at least one of said anvils at positions of said trackway other than said terminal positions.
